UNITED STATES PATENT OFFICE.

TEODORO LARREY, OF MEXICO, MEXICO, ASSIGNOR TO HIMSELF AND LUIS GODARD,
OF MEXICO, MEXICO.

STEAM SUPERHEATING UNIT.

Application filed June 18, 1926. Serial No. 116,896.

This invention relates to steam superheating units; and it involves certain improvements, hereinafter fully described, in the mounting of such units in a superheating system, particularly a system of the type disclosed in the prior application of Luis Godard and myself, No. 73,921, filed December 7, 1925.

According to the system described in that application, the tubular superheating units are mounted at one end in a so-called "deflector" or header and are constructed and arranged to provide for a stepwise or stage superheating action. With that object in view, the header is divided into a plurality of vertical chambers, and the aforesaid ends of the units pass transversely through these chambers and are formed with inlet and outlet ports or apertures which enable the saturated steam supplied to one chamber of the header to pass from that chamber into one group of units, circulate therethrough and escape in a superheated state into a second chamber. From the latter, the superheated steam enters and circulates through a second group of units and is then discharged into a third chamber, wherefrom it may be delivered to the cylinders of the locomotive or, if preferred, may first undergo a further stage or stages of superheating and then be supplied to the cylinders; the precise number of stages and, hence, the number of groups of tubes, being more or less immaterial.

In the earlier construction, however, the removal of the units for individual replacement, repair, cleaning and other purposes was impossible, due to their mounting; and it was usually necessary to disconnect the header and move it and the superheating tubes bodily away from the boiler in order to withdraw the tubes from the boiler flues, before detaching the superheating tubes from the header.

Such procedure entails, of course, considerable time and trouble, and it was with the object of avoiding the same that I have devised the present mounting, according to which the end of each unit has fitted on and secured to it a tapered or conical sleeve which, in turn, is removably fitted in a second tapered sleeve that extends through the several chambers of the header. The first-named or inner sleeve, due to this arrangement, can be withdrawn through the outer

sleeve, carrying with it the unit to which it is fastened, without requiring any shifting of the header itself or of the other units of the group of which it is a part; such operation, as well as the subsequent re-insertion of the sleeve, being effected readily and quickly by means of simple tools. Other and further objects and improvements will appear in the course of the following description.

In the accompanying drawing, Figure 1 is a diagrammatic side elevation of the invention installed in the smoke-box of a locomotive; and

Fig. 2 is an enlarged detail view, in vertical section, illustrating the mounting of one of the superheating units in the header.

Referring to Fig. 1, 1 indicates the smoke-box of the steam engine or locomotive, 2 the boiler wall, 3 the tube sheet and 4 the fire tubes or flues; the latter being of different diameters, as usual, and arranged in accordance therewith in different definite groups. The dry pipes 7 (of which only one appears) extend through openings in the tube sheet into the smoke-box and are connected by elbows 8 with the front chamber 9 of the deflector or header 10. The interior of the header is divided by partitions into a plurality of substantially-counterpart chambers, disposed one in front of another and extending from top to bottom of the header as in the earlier construction. There are four of these chambers in the construction illustrated, designated 9, 9', 9² and 9³; but such number is arbitrary and may be increased or decreased, according to the number of stages of superheating desired. Hence, the header itself, aside from its being provided with a plurality of internal chambers of the general character specified, forms, as to its structural details, no part of the actual invention which, on the contrary, resides primarily in the mounting of the superheating units, as subsequently explained.

The superheating units proper, which are generally designated 38, are virtually identical with those embodied in the earlier construction. That is to say, they are in the form of tubes which extend through the flues or fire tubes 4 of the boiler and are closed at opposite ends by plugs 30 and 31, and are partitioned longitudinally by flat horizontally-disposed bars 32 that abut at their

front ends against the front plugs 31 but terminate at their rear ends an appreciable distance short of the rear plugs 30; said bars being rigidly secured in position in any desired manner in the respective tubes 38. The port system with which the said tubes and related parts is provided, serves to effect communication between the successive chambers of the header in the same way as in the earlier construction and for precisely the same purpose—i. e., to obtain the required stage-heating of the steam, further reference thereto being made hereinafter.

According to my present invention, and as represented in Fig. 2, I fit on and rigidly secure to the front end of each superheating tube 38 a tapered or conical sleeve or bushing 40; the attachment between the two parts 38 and 40 being preferably effected by external and internal welds 41 and 42. The rear or inner end of the sleeve or cone is slightly enlarged, as indicated at 43, and a pair of annular enlargements or shoulders 44 and 45 is also provided at an intermediate point on the sleeve; the three parts 43, 44 and 45, which are slightly rounded, engaging with more or less friction against the tapered inner surface of a second or outer sleeve or bushing 46 into which the inner sleeve is fitted, for the purpose of retaining the latter in place. In addition to this friction lock, an additional centering or positioning means may be provided in the form of an annular rib or shoulder 47 of rounded section, located on the inner surface of sleeve 46 adjacent its rear end, and which is engaged by the enlarged end 43 of sleeve 40; but such rib can be omitted if preferred.

As shown in Fig. 2, the outer sleeve 46 is long enough to extend through all four chambers of the header and to project slightly beyond the same at opposite ends. The projecting inner or rear end of this sleeve is turned outward to form a circumferential flange 48, between which and the adjacent header wall a copper gasket 49 is interposed; while the projecting outer or front end is threaded, as indicated at 50, and has screwed on it a cap or cover 51 having a threaded central aperture 52, a similar gasket 53 being positioned between the front wall of the header and the edge of cap 51. The inner surface of sleeve 46 tapers, as previously stated, so that this sleeve likewise has, in effect, a conical form; the arrangement being such that the inward or rearward movement of sleeve 40 in sleeve 46 will cause the three enlargements 43, 44 and 45 on the former sleeve to bind against the inner surface of the other sleeve which, as will be understood, is of tapering or decreasing diameter from front to rear. Consequently, the superheater tube can be inserted through sleeve 46 and introduced into the flue tube 4, and will carry sleeve 40 (which is welded

to it) into the said sleeve 46, the two sleeves being ultimately locked together by their frictional engagement.

The front end of sleeve 40 may be closed by a plate or washer 54 having a central boss 55 on its outer face for engagement by the socketed inner end of a bolt or rod 56 which is utilized to force said sleeve into place in the outer sleeve 46. This bolt or rod is screwed through the central aperture 52 in cap 51 and is held in adjusted position by a fastening nut 57 and washer 58. When the parts 51 and 56 have been removed, a suitably-pronged tool (not shown) can be inserted through the end of sleeve 46 and hooked into perforations 59 formed in said plate 18, whereupon the latter can readily be withdrawn without affecting the position of the inner sleeve 40 in any way.

As has already been stated, the superheating tubes are provided with a port system which enables the steam supplied to one chamber of the header to enter the tubes of one group, circulate therethrough from front to rear and then back, and then discharge from that group into a second chamber, whence it passes into a second group of tubes, and so on from chamber to chamber. The last chamber of the header discharges the superheated steam through an elbow or similar connection 12 into the casing or box 13 of the throttle valve (the stem of which is indicated at 18); and from said casing, the steam is supplied through pipes 14 directly to the steam chests and thence to the cylinders. The passage of the steam from chamber to tube and from tube to chamber is the same for all the groups of tubes, and for that reason the illustration and description will be limited to a tube of one group which, in the arrangement represented in Fig. 2, receives steam from the third chamber 9² of the header and thereafter discharges it into the fourth or last chamber 9³.

Referring to the figure specified, it will be assumed that the saturated steam supplied to the first chamber 9 by the dry pipe 7 has passed from that chamber into and through one group of tubes, and has been converted into superheated steam during such passage; thereafter being discharged into the second chamber 9¹, then circulated through a second group of tubes, and then discharged into the third chamber 9². Starting with that chamber, the superheated steam passes into the tube 38 illustrated through registering openings 60, 61 and 62 formed, respectively, in the sleeves 46 and 40 and in the tube itself. It then circulates first rearward and then forward through the upper and lower compartments of the tube formed by the partition 32 and finally, on reaching the front end of the lower compartment, discharges through the registering ports or openings 130

63, 64 and 65 in the respective parts 38, 40 and 46 into the last chamber 9³ of the header from which, in turn, it escapes through elbow pipe 12 into the throttle casing. The 5 stage heating can, however, take place in the reverse order to that described, starting with chamber 9³ and ending with chamber 9, the result being precisely the same.

Due to the removable fitting of the inner 10 sleeves or cones 40 in the outer sleeves 46, and to their rigid attachment to the superheater tubes 38, as above described, it will be apparent that, once the cap 51 and connected parts have been removed, a pull 15 exerted in an outward direction on any one of the inner sleeves 40 will withdraw the latter and the superheater tube fastened to it bodily as a unit from the header and the flue tube. Hence any individual tube desired 20 can readily be removed at will for any of the purposes originally stated, and without requiring any displacement of the header. To facilitate this, the front end of each inner sleeve 40 may be formed with a pair of 25 lateral openings 66 into which a pulling tool can be hooked in the same manner as previously explained in connection with the removal of plate 54. Only one of the openings 66 appears in Fig. 2.

30 I claim as my invention:—

1. In a steam superheating system for steam engines, the combination of a header having its interior partitioned to form a plurality of vertical chambers disposed one

in front of another; an open-ended tapered sleeve mounted in the header and extending transversely through the several chambers thereof; an open-ended tapered sleeve frictionally engaged in the first-named sleeve and removable through the front end thereof, said sleeves having registering inlet ports which open into one chamber and registering outlet ports which open into another chamber; a tubular superheating unit inserted into and rigidly secured in the rear end of 40 the inner sleeve to be withdrawn with the same through the said front end of the outer sleeve; and releasable fastening means for holding the inner sleeve against withdrawal.

2. A steam superheating system, according to claim 1, in which the inner sleeve is provided with openings to receive the end of a pulling tool when the fastening means has been disengaged, to enable said sleeve and its connected unit to be withdrawn 55 through the outer sleeve.

3. A steam superheating system, according to claim 1, in which the inner sleeve is provided at its front end with a closure element against which a forcing element 60 forming part of the fastening means is adapted to be pressed when said fastening means has been positioned, to enable said sleeve to be pushed into place in the outer sleeve after it has been inserted into said 65 outer sleeve.

In testimony whereof I affix my signature.
TEODORO LARREY.
